WIRE CLIP FOR PAPERS

William H. Smith, Rochester, N. Y.

Application April 2, 1935, Serial No. 14,293

7 Claims. (Cl. 24—261)

The object of this invention is to provide a new and improved form of paper clip or a clip that is adapted to hold several sheets of paper together.

5 Another object of the invention is to provide a clip that will engage the papers in a way that will protect the clip itself from being disturbed in its position in engagement with the papers.

Another object of the invention is to provide a 10 clip that is easily engaged and disengaged with the paper, and can be used to hold together a large number of papers.

Another object of the invention is to provide a clip having two free ends of unequal length.

15 Another object is to provide a clip having points, the ends of which can be embedded in or under the outer sheets of paper.

These and other objects of the invention will be illustrated in the drawing, described in the 20 specification and pointed out in the claims at the end thereof.

In the drawing:

Figure 1 is a front elevation of my clip shown in engagement with a number of sheets of paper.

25 Figure 2 is a vertical section on the line 2x—2x of Figure 1.

Figure 3 is a top plan view of the clip and paper shown in Figure 1.

Figure 4 shows a plan view of a modified form 30 of the clip.

Figures 5, 6 and 7 show clips in which the free ends of the clips are inturned toward each other so that they can penetrate one or more sheets of paper.

35 Figure 8 shows another modified form of the clip in which the free ends of the clip are pin pointed and the intermediate portion is ring-shaped.

Figures 9, 10 and 11 show further modifications 40 of the clip.

In Figure 12 I have shown one of the clips of Figures 5, 6 and 7 with the points thereof embedded under the outer sheets of paper.

45 In the drawing like reference numerals indicate like parts.

The clips shown in the several figures of the drawing are preferably made of a single piece of wire.

In the clip shown in Figure 1, the wire is bent 50 on itself at a point nearly intermediate its length to form a rounded tongue or yoke 1 with parallel sides 2 and 3 and 4 and 5. These parallel sides are connected by diverging sides 6 and 7. At the opposite end of the clip the wire is bent to 55 form the radial arms 8 and 9, which extend to-

ward each other, and on the ends of which are bent the inturned points 10 and 11, which points are of unequal length and extend substantially parallel to each other.

It is also understood that all the elements of 5 this clip normally lie substantially in the same plane. When this clip is used to hold a number of sheets of paper together, the tongue 1 is first inserted between the sheets of paper and the clip is pushed down until the long point 11 is 10 almost in engagement with the paper, and then this point is sprung out to one side of the papers and the clip is pushed into further engagement until the short point 10 is in engagement with the papers, and this point is swung out to engage the 15 opposite side of the bunch of papers, after which the clip is pushed into the position shown in Figures 2 and 3, in which case the arms 8 and 9 will assume the diagonal position shown in Figure 3. 20

These arms are of sufficient length that they permit the clip to spring to a considerable angle without exceeding the elastic limit of the wire, so that when the clip is withdrawn the parts will all resume their original position in 25 substantially the same plane. This is true of all of the other clips shown in the various figures in which the radial arms at the top of the clip are made of considerable length so that they can be sprung away from each other to a considerable 30 angle, and can be used to engage a large number of sheets of paper.

As shown in Figure 2, the ends of the points 10 and 11 are beveled as indicated at 12 and 13. These beveled points will naturally ride close to 35 the paper and conform thereto, so that another sheet of paper cannot be accidentally slipped in under either of these points.

In Figure 4 I have shown a clip having a tongue 40 15 with sides 16 and 17 diverging at a small angle and the sides 18 and 19 diverging at a larger angle. To these sides are connected the radial arms 20 and 21, each of which has the long point 22 and the short point 23 formed on the end thereof. 45 These points may be left blunt, if so desired.

In Figure 5 I have shown a similar clip having a tongue 25 with the diverging sides 26, 27 connected thereto diverging at a small angle, and the sides 28 and 29 diverging at a larger angle, and the parallel sides 30 and 31. To these are connected the radial arms 32 and 33 with the points 34 and 35 thereon. At the end of each of these points the wire is rounded with a curve of rather long radius with the ends of the points pointing 50 55

towards each other. These points 34 and 35 are preferably pin-pointed.

In Figure 6 I have shown a tongue 40 having the sides 41 and 42 diverging at a small angle and the sides 43 and 44 diverging at a bigger angle, on which are the radial arms 45 and 46 from which extend downwardly the points 47 and 48, the ends of which points are curved toward each other and are left blunt.

10 In Figure 7 the clip is formed with a tongue 50 with the sides 51 and 52 diverging at a small angle and the sides 53 and 54 diverging at a larger angle. To these are connected the parallel sides 55 and 56, on which are formed the radial arms 57 and 58, from the ends of which extend downwardly the points 59 and 60. The ends of these points are curved, as shown in Figure 7. In this figure the radial arms 57 and 58 are extended sufficiently so that the points 59 and 60 overlap each other, one of them lying to the right of the plane of the clip and the other lying to the left of the plane of the clip.

The inturned points shown in Figures 5, 6 and 7 serve to embed the extreme ends of the points in the paper to that extent that other sheets of paper will ride over them and will not become engaged with them.

15 In Figure 8 I have shown a clip formed with a tongue 61 that is ring-shaped, from which extend the parallel sides 62 and 63 on which are the diverging sides 64 and 65. On these are provided the parallel sides 66 and 67, to which are connected the radial arms 68 and 69. On these arms are provided the points 70 and 71 which extend inwardly parallel to each other and are shown pin-pointed.

20 In Figure 9 I have shown a clip with a tongue 72 having the sides 73 and 74 diverging at a small angle and the sides 75 and 76 diverging at a larger angle, on which are the radial arms 77 and 78 extending toward each other on which are provided the downwardly projecting points 79 and 80.

25 In Figure 10 I have shown a clip having a wide half-round tongue 81, with the parallel sides 82 and 83, on which are the radial arms 84 and 85, on which in turn are provided the downturned points 86 and 87.

30 In Figure 11 I have shown a clip having a ring-shaped contour 90, the open ends of which are provided with the down-turned points 91 and 92.

35 In all of these cases the inturned or downturned points are made of unequal length, so that the clip may be inserted first with the tongue in engagement between the papers. Then the long point is engaged on one side of the papers and the short point is engaged on the other side of the papers. In this way the three parts of the clip, namely, the tongue and the two points, are engaged successively, step by step, until they are properly engaged with the bunch of papers, after which the clip is pressed into its final position shown in Figures 1, 2 and 3.

40 It is obvious, too, that any of these points, other than the blunt points, instead of being left on the outside of the bunch of papers as shown in Figure 2, may be thrust through one or more of the outer sheets of paper before the clip is pushed to its final position, and then when the 45 clip is pushed to its final position the points will be concealed under the outer sheets of paper so that by no possibility can other sheets of paper become engaged with these points. In this case the points can be engaged so that a quarter of an 50 inch or more of the end of the point will be con-

cealed below the outer sheets of paper, as is shown in Figure 12.

I claim:

1. A paper clip made of a piece of wire bent to form a tongue at one end and a base at the other end, the ends of the wire being bent inwardly from the base toward the tongue at a point substantially at the center of said base and lying substantially parallel to each other, the inturned ends being of unequal length and terminating short of the tip of the tongue. 5

2. A paper clip made of a piece of wire bent to form a tongue at one end and a base at the other end, the ends of the wire being bent inwardly from the base toward the tongue at a point substantially at the center of said base and lying substantially parallel to each other, the inturned ends being of unequal length and terminating short of the tip of the tongue, the tips of the ends being bent somewhat transversely to the plane of the clip and opposite to each other. 15

3. A paper clip made of a piece of wire bent to form a tongue at one end and a base at the other end, the ends of the wire being bent inwardly from the base toward the tongue at a point substantially at the center of said base and lying substantially parallel to each other, the inturned ends being of unequal length and terminating short of the tip of the tongue, the ends of the wire being pointed and being adapted to penetrate the paper. 25

4. A paper clip made of a piece of wire bent to form a tongue at one end and a base at the other end, the free ends of the wire being bent inwardly from substantially the center of the base toward the tongue, and stopping short of the inner end of the tongue by a substantial distance, and lying substantially parallel to each other, the free inturned ends of the wire being of unequal length. 30

40 5. A paper clip made of a piece of wire bent to form a tongue at one end and a base at the other end, the free ends of the wire being bent inwardly from substantially the center of the base toward the tongue, and stopping short of the inner end of the tongue by a substantial distance, and lying substantially parallel to each other, the free inturned ends of the wire being of unequal length, one of said ends being capable of being sprung transversely to the plane of the 45 clip in one direction and the other end being capable of being sprung transversely to the plane of the clip in the other direction.

6. A paper clip made of a piece of wire bent substantially at its midpoint to form a U shaped 55 configuration and having the free end portions bent to form a pair of smaller inverted U shaped configurations, the ends of the wire extending generally straight and parallel and substantially at the center line of said first named U and 60 short of the loop thereof, and one of said ends being longer than the other.

7. A paper clip made of a piece of wire bent double to form a tongue and having the free end portions bent towards one another and thence 65 inward substantially along the axis of the tongue, the ends terminating short of the loop of the tongue and being of unequal length, whereby in engaging the clip with a plurality of leaves of paper, the tongue may first be inserted between 70 the leaves of paper, the larger free end then passed over one side of the leaves and the shorter free end thereafter passed over the other side of the leaves.
